UNITED STATES PATENT OFFICE.

DANIEL J. REESE, OF SCRANTON, PENNSYLVANIA.

DRAIN-PIPE FLUSHER.

1,110,715.

Specification of Letters Patent. Patented Sept. 15, 1914.

Application filed June 5, 1914. Serial No. 843,291.

To all whom it may concern:

Be it known that I, DANIEL J. REESE, a citizen of the United States, residing at Scranton, in the county of Lackawanna and 5 State of Pennsylvania, have invented a new and useful Drain-Pipe Flusher, of which the following is a specification.

The present invention appertains to a flushing device for the drain, waste and over-flow pipes of sinks, wash bowls, bath tubs, and the like, and aims to provide a novel and improved appliance of that nature which is peculiarly adapted for cleaning or clearing out the outlet pipes of sinks, wash bowls, bath tubs and the like.

Another object of the present invention is to provide a flushing device of unique construction, which is adapted for connection with a faucet, or other source of water, 20 whereby the greasy matter, sediment, and other refuse within a drain or discharge pipe may be washed out, the present device also being adapted to serve as a pump or suction device for dislodging any obstruction that 25 tends to plug up the drain pipe.

A further object of the present invention is to provide a flushing device, including novel means for creating a whirling motion of the stream of water, to facilitate the clearing of the drain pipe.

It is also within the scope of the present invention to provide a device of the nature specified, which will be comparatively simple, and inexpensive in construction, as well 30 as being simple, practical, serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 40 the scope of what is claimed, without departing from the spirit of the invention.

The invention has been illustrated in its preferred embodiment in the accompanying drawing, wherein:—

50 Figure 1 is a sectional view of the improved flushing device, the hose or flexible portion being broken away. Fig. 2 is a reduced view of the device as applied to a wash bowl. Fig. 3 is a cross section of the device, taken on the line 3—3 of Fig. 1.

In carrying out the present invention,

there is provided a bell 1, constructed of rubber or other flexible material, and having its rim or margin provided with an inturned annular flange or lip 2 adapted to conform 60 to the surface of a sink, wash bowl, bath tub, or the like, and to provide an effective seal or closure when the bell 1 is applied to a sink, wash bowl or the like, over the drain or outlet pipe. The bell 1 is provided at its 65 crest with an upturned tubular or collar portion 3 which embraces a nozzle 4 projecting into the bell 1. The nozzle 4 which fits snugly within the tubular portion or collar 3 of the bell 1, is contracted or reduced in diameter adjacent its lower or free end, as at 5, and is tapered downwardly from adjacent its upper end to the contracted portion 5, as at 6. The lower end of the nozzle 4, below the contracted portion 5, 70 is flared, as at 7, while the upper or butt end of the nozzle is provided with an annular enlarged and threaded portion 8 above the tubular or collar portion 3 of the bell. Disposed, within the nozzle 4, is a spiral or 75 helical web or member 9 which is integral with a longitudinal or axial spindle or stem 10 disposed within the nozzle 4. The spiral member 9 is shaped to conform snugly to the interior of the nozzle 4, the lower end of the 80 spiral member 9 and its stem 10 being slightly flared or enlarged, as at 11 within the flared mouth 7 of the nozzle 4, to cause the stream of water issuing from the nozzle 4 to spread.

In order to mount the spiral member 9 within the nozzle 4, a flat ring 12, with which the upper end of the spiral member 9 is integral, is seated upon the upper end 8 of the nozzle 4, and is provided with the opening 13 above the upper end of the spiral member 9. The ring 12 is clamped or seated upon the upper end 8 of the nozzle 4 by means of a union or nut 14 having a lower threaded socket 15 threadedly engaging over 100 the upper end of the nozzle and seating upon the ring 12. The union or nut 14 is provided with an upstanding nipple 16, projecting away from the socket 15, and adapted to receive thereover, one end of a hose 17 105 of suitable length. The end of the hose 17 is clamped upon the nipple 16, by means of a band 18 embracing the hose 17 about the nipple 16. The tubular or collar portion 3 of the bell 1 is preferably clamped about the 110 body portion of the nozzle 4 by means of a band 19 embracing the tubular portion 3.

The construction of the present flushing device is such, that it is adapted for application to various styles of sinks, wash basins, bath tubs, and other fixtures, to clean out various sizes and shapes of drain, waste and overflow pipes. As an illustration of a particular application of the device, reference being had to Fig. 2, the free end of the hose 17 may be applied to the faucet 20 of a wash bowl 21, and the rim or margin of the bell 1 is adapted to snugly fit the interior of the bowl 21 surrounding the drain outlet or pipe 22, it being observed that when the central tubular portion 3 of the bell 1 is pressed toward the bowl, the flange or lip 2 of the bell will be caused to tightly fit the bowl or basin 21 to effect a perfect closure between the bell 1 and bowl. Now, when the faucet 20 is opened, to admit water into the hose 17, the water being under pressure, will be forced through the nozzle 4 and into the drain pipe 22. The spiral member or core 9 being disposed within the nozzle 4, will establish a whirling motion of the water as it passes through and leaves the nozzle 4, the lower end 11 of the core 9 serving to spread the whirling stream of water as it is discharged into the drain pipe 22, and as a consequence, the water will strike the walls of the drain pipe 22. In this manner, the water will continue to whirl within the drain pipe 22, to facilitate clearing out the greasy or corroded matter which lines the drain pipe. By pressing the bell 1 downwardly, the tip or mouth 7 of the nozzle may be projected into the end of the drain pipe, the usual strainer or sieve having been removed, whereby the action of the water within the drain pipe 22 will even be more effective.

Another salient or cardinal feature of the present invention, resides in the fact that when the water has been let into the hose 17, bell 1 and drain pipe 22, the faucet 20 may be closed, and then by reciprocating the cen-

tral portion of the bell 1, a pumping or sucking action may be established through the drain pipe 22, to dislodge any accumulation within the drain pipe 22, which tends to block or clog the same.

The present device may also be applied with equal success and propriety to other fixtures, such as kitchen sinks, bath tubs, and the like, and is convenient and practical in its use, as well as being sanitary and simple.

Having thus described the invention, what is claimed as new is:—

1. In a device of the character described, a bell, a nozzle projecting thereinto, the nozzle being contracted adjacent its inner end and the inner end of the nozzle being flared, and a spiral member mounted within the nozzle and conforming to the interior thereof, the inner end of the spiral member being flared within the flared inner end of the nozzle.

2. In a device of the character described, a bell, a nozzle projecting thereinto, a spiral member disposed within the nozzle and having a portion at its outer end seating against the outer end of the nozzle, and means engaged to the outer end of the nozzle for clamping the said portion thereagainst.

3. In a device of the character described, a bell, a nozzle projecting thereinto, a spiral member disposed within the nozzle and having a ring at its outer end seating against the outer end of the nozzle, and a socket nut threaded upon the outer end of the nozzle to clamp the said ring thereagainst, and having a hose attaching nipple.

In testimony that I claim the foregoing as my own, I have hereto affixed my signature in the presence of two witnesses.

DANIEL J. REESE.
